W. H. WAKEFIELD

DETECTOR FOR BOBBINS WITH RINGS CONTROLLED BY BOX MOTION

Filed Dec. 30, 1924

UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DETECTOR FOR BOBBINS WITH RINGS CONTROLLED BY BOX MOTION.

Application filed December 30, 1924. Serial No. 758,906.

This invention relates to improvements in detectors for use with a plurality of shuttles to detect the condition of the yarn therein and more particularly to a detector rendered more sensitive when cooperating with a shuttle provided with fine yarn than when cooperating with a shuttle provided with coarse yarn. My present invention relates more particularly to the type of detector which cooperates with a movable member on the bobbin.

It is the general object of my present invention to provide a detector of the type specified having provision for varying the pressure of the detector against the movable member on the bobbins.

It is a further object of my invention to provide a weft detector which will normally retain the same setting for all degrees of sensitiveness thereof.

With these and other objects in view which will appear as the description proceeds, my invention resides in the combination and arrangement of parts hereinafter described and set forth in the claims.

A preferred form of my invention is shown in the drawings in which—

Fig. 1 is a plan view of my improved mechanism,

Fig. 2 is a side elevation thereof;

Fig. 3 is a detail plan view showing the action of the detecting member when the weft is substantially exhausted,

Fig. 4 is a front elevation of a portion of a loom having my invention applied thereto, and

Fig. 5 is an enlarged horizontal section on line 5—5 of Fig. 4.

Referring to the drawings, I have shown parts of a weft detecting mechanism similar in general construction and method of operation to that found in the Ryon Patent No. 972,722, issued October 11, 1910.

The parts shown comprise a detecting member 10 beveled on the rear end thereof and slidable in a casing 11, adjustably secured upon a bracket 12 supported by the loom side L. At its forward end, the member 10 is connected by a link 13 to an arm 14 adjustably secured to a cross rod 15 supported in bearings 16 and 17 on the bracket

12. A spring 18 on the rod 15 presses the arm 14 rearward, causing a stop screw 19 to normally engage the front face of the casing 11.

A controller rod 20 is pivoted on a second arm 21 secured to the cross rod 15. The rod 20 normally extends into or across a groove or slot 22 in an upward projection 23 of the bracket 12. A lever 24 is mounted for vertical movement in the slot 22 and will engage the rod 20 on its downward movement unless the latter is withdrawn from the slot 22 by the action of the detecting member 10. Engagement of the rod 20 by the lever 24 indicates substantial weft exhaustion and initiates a change in the operation of the loom, such as a transfer of weft carriers.

The weft carrier W is of special construction, and as shown in Figs. 1 and 3, adjacent its head 25, is provided with a cylindrical body or barrel portion 26 (Fig. 3), a part of which is provided with grooves 27 or is otherwise roughened for a special purpose.

A plurality of beveled rings 28 are mounted to slide freely on the barrel 26 and an additional sliding member 30 is also mounted thereon. The member 30 has a beveled head or flange 31 and also has a cylindrical shank or hub portion 32 slidable on the barrel 26. The surface of the part 32 may also be grooved or roughened as indicated at 29 in Fig. 3.

On one or both sides of the hub 32, an opening or slot 33 is provided, and a stud 34 is inserted in the barrel 26 within one of the openings 33 to limit sliding movement of the member 30.

When the weft or filling is to be wound on the weft carrier, the rings 28 and sliding member 30 are seated against the head 25 as shown in Fig. 1. The openings 33 are preferably of such circumferential width that the first layers of filling F will engage the grooves 27 in the roughened surface of the barrel 26, as well as the grooves 29 on the hub 32, thus holding the sliding rings from displacement.

The parts are so positioned in the loom that the detecting member 10 is engaged by the rings 28 or the flange 31 as the weft car-

rier comes forward, and the member 10 and the indicating rod 20 are thus moved forward and the lever 24 is free to swing in its slot or groove 22 when sufficient yarn is present.

This method of operation continues until the weft is substantially exhausted on the weft carrier W. The wedge-like action of the member 10, exerted against the rings 28 and the flange 31, then separates these parts as shown in Fig. 3, permitting the member 10 to enter between the rings and thus remain unmoved from rearward position. The rod 20 is thus left in the path of the lever 24 and weft exhaustion is indicated. The abrupt and material change in diameter when the rings slip also avoids the necessity for close adjustment. The matter thus far described is similar to the detector set forth in Patent No. 1,502,413 to Turner.

My invention relates more particularly to the application of the above feeler to a box loom and by referring to Figs. 1 and 4, it will be seen that I have provided means to vary the pressure of spring 18. Referring to Fig. 1 it will be seen that the shaft 15 has adjustably secured thereto a collar 50 which receives one end of the spring 18 and also has mounted thereon an arm 51 which receives the other end of the spring 18, said arm being pivotally connected to a rod head 52 as at 53. The spring 18 normally tends to lift the inner end of the arm 51 and also tends to hold the controller 20 under the floating lever 24.

In order to vary the pressure of the sliding detector 10 I vary the position of the arm 51 so that the pressure exerted on said arm by the collar 50 will be greater under certain conditions than under others. The mechanism for moving the arm 51 vertically is shown in Figs. 1, 2, and 4, where it will be seen that a rocker shaft 54 is rotatably mounted in the frame L and has secured thereto a picker foot 55.

A box rod 56 of any approved construction carries at the upper end thereof a multiple of boxes B, four boxes being shown in the present instance. Secured to the box rod is an arm 57 the upper end of which is connected as at 58 to a slide 59, the lower end of the slide being guided in a bearing 60, said slide bar being held in the bearing by plates 61. The bearing is secured to the picker foot 55 so that the box rod, slide, and bearing move as a unit about the rocker shaft 54.

The mechanism for determining when the pressure of the detector wires should be reduced or increased comprises a lever 62 pivoted as at 63 to the picker foot and provided with a face 64 which is normally held toward the slide block 59 by means of spring 18. Removably secured to the slide block are tappets 65 said tappets being the same height

when it is desired to have but two degrees of pressure or being of variable heights when it is desired to have more degrees of pressure. Attached to the lower end of the lever 62 is a flexible connector 66 which extends across the loom and around a sheave 67 and has the upper end thereof connected to rod head 52.

The mechanism associated with the box rod may be of the form set forth in detail in my co-pending application Serial Number 28, filed Jan. 2, 1925.

It will be seen that the varying positions of the rod head 52 will vary the pressure of the spring 18 so that the latter will cause the pressure to be greater when coarse yarn is being woven than when fine yarn is being woven. The force therefore tending to move the slide 30 longitudinally along the bobbin will vary according to the character of yarn wound on the bobbin.

From the foregoing it will be seen that I have provided means for varying the pressure of the detector against the rings on the bobbin to make said detector more sensitive when weaving fine yarn than when weaving coarse yarn. It will also be noted that this change in the sensitiveness of the detector is effected by parts which are not in contact with the yarn and that the detector and controller rod retain the same setting for the varying degrees of sensitiveness.

Having thus described my invention it will be apparent that changes and modifications may be made therein by those skilled in the art without departing from the spirit and scope of the invention and I do not wish to be limited to the details herein disclosed, but what I claim is:

1. In a loom having a plurality of shifting shuttle boxes and shuttles each of which may become active and each of said shuttles being provided with a bobbin having a relatively movable member thereon, a detector depending upon the relative movement of the member with respect to the bobbin to give indication of substantial weft exhaustion, and means under control of the shuttle boxes to exert a variable pressure on said member tending to move the same relatively to the bobbin.

2. In a loom having a plurality of shifting shuttle boxes and shuttles each of which may become active and each of said shuttles being provided with a bobbin having relatively movable members thereon, a detector depending upon the separation of the members on the bobbin to give indication of substantial weft exhaustion, and means under control of the shuttle boxes to vary the pressure tending to separate said members.

3. In a loom having a plurality of shifting shuttle boxes and shuttles each of which is provided with a bobbin having a member movable thereon, a detector moved to in-

operative position when engaged by said movable member when the latter is in normal position and effective to give indication of weft exhaustion when said member moves 5 with respect to the bobbin, and means under control of the shuttle boxes to vary the force tending to move said member with respect to the bobbin.

4. In a loom having a plurality of shifting shuttle boxes and shuttles each of which may become active, a detecting mechanism formed in part by a member mounted independently of the shuttle and in part by a member carried by the shuttle and tending 10 to move with respect to the shuttle under influence of the first named member, and means under control of the shuttle boxes to vary the tendency of the first named member to move the second named member with respect 15 to the shuttle.

5. In a loom having shuttle boxes for a plurality of shuttles each of which may become active, a control member moving with the shuttle boxes and assuming different positions depending upon which shuttle is active, a detector to cooperate with each shuttle when active, a member carried by each shuttle movable with respect to the shuttle 20 at substantial weft exhaustion under influence of the detector, and means under control of the shuttle boxes to vary the tendency of the detector to move the member in the active shuttle.

6. In a detector mechanism for looms operating with a plurality of shuttle boxes and shuttles each of which is provided with a bobbin having a portion occupied by yarn and a movable portion free from yarn, a detector to cooperate with a movable portion 35 of the bobbin free from the yarn, and means controlled by the shuttle boxes to vary the pressure of the detector against the movable part of the bobbin.

7. In a loom having shifting shuttle boxes 40 to accommodate a plurality of shuttles each of which may become active, a bobbin located in each shuttle having rings slidably mounted thereon, a detector to cooperate with the rings on the bobbins of the active shuttle 45 to indicate substantial weft exhaustion, and means dependent upon the position of the

shifting shuttle boxes to vary the pressure of the detector against the rings.

8. In a loom having shifting shuttle boxes for a plurality of shuttles which may become active one at a time, a control member moving with the shuttle boxes and assuming different positions depending upon the position of the shifting boxes, a detector to cooperate with each shuttle when active, a member carried by each shuttle movable with respect to the shuttle at substantial weft exhaustion under influence of the detector, and a single resilient device interposed between the control member and the detector and dependent upon which shuttle box is active to vary the tendency of the detector to move the member in the active shuttle. 55

9. In a loom having a plurality of shifting shuttle boxes and shuttles which may become active one at a time, detecting mechanism having a relatively stationary member to cooperate with each shuttle when active, each shuttle having a member movable with respect to the shuttle to be engaged by the first 60 named member and tending to move under influence thereof, and means acting in timed relation with the shuttle boxes and dependent upon which shuttle box is in active position to vary the force exerted by the stationary member on the movable shuttle member, said stationary member of the detector giving an indication of weft exhaustion when the shuttle member moves under influence of the stationary detector. 70

10. In a loom having a plurality of shuttle boxes and shuttles each of which may become active and each of which is provided with a bobbin having beveled rings slidably mounted thereon, a detector to engage 75 the beveled rings of each shuttle when active to exert a pressure thereon longitudinally of the bobbin, means acting in timed relation with the active shuttle and dependent upon which shuttle box is active to vary the pressure 80 exerted against the beveled rings of the active shuttle, and means to give an indication of weft exhaustion when the rings move longitudinally of the bobbin. 90

In testimony whereof I have hereunto affixed my signature. 95
